UNITED STATES PATENT OFFICE.

JACOB MARKELL, OF BROOKLYN, ASSIGNOR TO HERMAN TAPPAN, OF NEW YORK, N. Y.

DESIGN FOR A PERFUMERY-HOLDER.

SPECIFICATION forming part of Design No. 21,925, dated October 25, 1892.

Application filed September 24, 1892. Serial No. 446,840. Term of patent 3½ years.

To all whom it may concern:

Be it known that I, JACOB MARKELL, a citizen of the United States, residing at Brooklyn, in the county of Kings and State of New York, have invented and produced a new and original Design for a Perfumery-Holder, of which the following is a specification, reference being had to the accompanying drawing, forming part thereof.

10 The figure is a perspective view showing my design.

The leading feature of the design consists in the representation of a cycle A and the part human-being-like figure B.

I claim—
The design for a perfumery-holder, as herein shown and described.

JACOB MARKELL.
